(57) **CLAIM**

The ornamental design for a cervical collar, as shown and described.

DESCRIPTION

FIG. 1 is a first perspective view of the cervical collar according to the invention.

FIG. 2 is a front elevational view according to the cervical collar of FIG. 1.

FIG. 3 is a rear elevational view according to the cervical collar of FIG. 1.

FIG. 4 is a first side elevational view according to the cervical collar of FIG. 1.

FIG. 5 is a second side elevational view according to the cervical collar of FIG. 1.

FIG. 6 is a top plan view according to the cervical collar of FIG. 1; and,

FIG. 7 is a bottom plan view according to the cervical collar of FIG. 1.

The broken lines are included for the purpose of illustrating environmental structure and form no part of the claimed design.
